United States Patent Office.

WILLIAM M. YOUNG, M. D., OF TREMPEALEAU COUNTY, WISCONSIN.

Letters Patent No. 72,710, dated December 24, 1867.

IMPROVEMENT IN ABDOMINAL SUPPORTERS.

The Schedule referred to in these Letters Patent and making part of the same.

TO ALL TO WHOM IT MAY CONCERN:

Be it remembered that I, WILLIAM M. YOUNG, of the county of Trempealeau, and State of Wisconsin, have invented a new and useful Machine for an Abdominal Support, for the treatment of *prolapsus uteri*; and I do hereby declare that the following is a full, clear, and exact description of the construction and operation of the same, reference being had to the accompanying drawing, making a part of this specification, in which—

Figure 1 marks the front view of the abdominal plate, the size of which is to be about eight inches across and seven inches deep, and nearly square at its upper end, and rounding at its lower end, its upper or square end being in shape convexo-concave, and its lower or rounding end being concavo-convex, this plate to be made of tin, covered with sheep-skin, buck-skin, or calf.

Figure 2 represents the depression of abdominal plate under the springs, which depression is about three inches by five in extent, and near the lower centre of the plate.

Figure 3 represents the form of the bend, or the convexity of the plate near its lateral margin.

Figure 4 represents one-half inch to be lapped over the edge, so as to strengthen the plate, but is not seen after the plate is covered.

Figure 5 represents the extreme margins of the plate, which turn up.

Figure 6 represents steel springs, about one-half inch broad, and thin. These springs stand out about one and one-half inch, at their centres, from the abdominal plate, and pass entirely across it horizontally, and are riveted to its outer edges.

Figure 7 represents the front half of the body-band, which is about seventeen inches in length, is made of steel, about one-quarter of an inch square, flattened at each end, and bent, about three inches from each end, at nearly right angles with its centre. In the centre of this band is fastened the abdominal plate, by rivet or small screw.

Figure 8 represents the small slides, which are slipped over the ends of band 7 before the pins, marked 9, are fastened in. These slides are used in fastening bands 7 and 10 together.

Figure 9 represents the small pins fastened to the front body-band, and to which are buttoned the straps, marked 12.

Figure 10 represents the rear half of the body-band, in shape the same as band above described, marked 7, its length thirteen inches, flattened at each end, and bent, two inches from the ends, nearly at right angles with its centres. To each end of this band are firmly attached the straps, marked 12. This band is also perforated several times at fig. 11. Through these perforations are passed small screws, fastening on the pads, marked 13.

Figure 12 represents the leather straps which fasten together the front and rear portions of the body-band. These straps are also perforated, that the circumference of the entire band may be enlarged or diminished at pleasure.

Figure 13 represents the pads, which are fastened by a small screw, passing through the perforations, marked 11, and into a small nut fixed on the centre of the pad. These pads are about three inches by two and one-half in breadth, being nearly oblong in shape. The back part of the pad is tin; the front, flannel-stuffed. These pads may be moved along the band, marked 10, to the right or left, as necessity may require.

Figure 14 represents the small nut concealed in the centre of the pads.

Figure 15 represents the perforations around the margin of the pads, through which are fastened the covers.

The several parts above described, when put together, as in Figure 16, and adjusted to the body, form a perfect support to the abdomen and womb. The lower part of the abdominal plate supports the womb in its proper place. The upper part supports the abdominal viscera, and gives the womb a chance to acquire its tone.

It is intended to have the band set clear from the body, so that the pressure will be upon the abdominal plate and the pads. The perforations in the leather straps regulate the pressure.

What I claim as my invention, and desire to secure by Letters Patent, is—

The form or shape of the abdominal plate, and the form and construction of the body-band.

Dated Galesville, Wisconsin, September 19, 1867.

WILLIAM M. YOUNG, M. D.
